COMBINED COAT AND SKIRT HANGER

Elmo Hall, Denver, Colo.

Application August 9, 1944, Serial No. 548,675

4 Claims. (Cl. 223—91)

This invention relates to improvements in coat hangers and has reference more particularly to a hanger that can be employed in connection with skirts and stockings as well as with coats.

The ordinary coat hanger is usually made from wire and has two oppositely extending arms provided at their center points with a hook by means of which the hanger can be supported from a bar or other supporting means. Such coat hangers are well known and are often provided with clothes pins or other clips for supporting trousers.

It is the object of this invention to produce a modified and improved form of coat hanger which is provided with four arms that are adjustably connected with the supporting element so that they may project in four separate directions and spaced ninety degrees apart, or which may be folded into the form of an ordinary coat hanger in which two of the arms project from opposite sides of the supporting means.

Another object of this invention is to produce a coat hanger which can be readily disassembled for transportation and which will therefore be well adapted for travelers as it can be packed into a small space when not in use.

Another object of this invention is to produce a coat hanger in which the four arms can be positioned, either at right angles towards each other, or in substantially parallel planes and which is provided with means for holding them in either of the two positions.

A still further object of the invention is to produce a coat hanger in which the arms are so constructed that they can not be easily disconnected from the supporting element.

The above and other objects that may become apparent as this description proceeds are attained by means of a construction and an arrangement of parts that will now be described in detail and for this purpose reference will be had to the accompanying drawing in which the invention has been illustrated in its preferred form, and in which:

Figure 1 is a perspective view of the hanger showing the parts in expanded position;

Figure 2 is a top view of the hanger shown in Figure 1, looking in the direction of plane 2—2, Figure 1;

Figure 3 is a side elevation of the hanger showing the same in folded position and looking in the direction of arrow 3—3, Figure 4;

Figure 4 is a top plan view looking in the direction of arrow 4, in Figure 3;

Figure 5 is a fragmentary diametrical section 55 23 that laps the under surface of the plate 13.

to an enlarged scale and shows more clearly the construction of the parts;

Figure 6 is a section taken on line 6—6, Figure 5;

Figure 7 is a section taken on line 7—7, Figure 6;

Figure 8 is a section taken on line 8—8, Figure 1, and illustrates one form of a clip that is suitable for use with the hanger; and

Figure 9 is a side elevation looking in the direction of arrow 9, Figure 8.

In the drawing, reference numeral 10 designates a supporting bar and extending downwardly from this bar is a hanger constructed in accordance with this invention. The hanger consists of a vertical supporting element 11 having a hook 12 that engages the supporting bar. Secured to the supporting element are two disks 13 and 14. These disks may be duplicates, or they may differ slightly from each other in a manner which will hereinafter appear. Each disk has been shown as provided with four holes 15 that are spaced ninety degrees apart. The disks are secured to the supporting element 11 by means of solder or other means 16. The means for securing the disks 13 and 14 to the bar 11, which has been shown in the drawing, is merely illustrative, and any other suitable means for this purpose may be employed. The disks should preferably be so secured to bar 11 that they lie in planes perpendicular to the supporting element. In Figure 6, a top plan view of disk 14 has been shown and from this it will be observed that depressed areas 17 extend radially from the holes 15. When the supporting arms, which will presently be described, are in position, they will be held in radial position by these depressions. Extending at angles w to the depression 17, are other depressions 18 that serve to hold the arms in the position shown in Figure 4. The supporting arms, of which four have been shown, are formed from a steel wire which is preferably quite resilient and of considerable strength. The arms are bent into what may be loosely designated V-shape, the vertices being indicated by reference numerals 19. The lower, or compression element of each arm has been designated by reference numeral 20 and the tension element by reference numeral 21. That portion designated by 20 is somewhat shorter than 21 so that when the arms are in position, the parts 20 will lie substantially in the same plane. The ends of parts 20 have a compound curve as indicated at 22 in Figure 5 and terminate in an end portion

50 55 23 that laps the under surface of the plate 13.

The ends of the tension elements are bent downwardly as indicated at 24 and terminate in a short hook 25. The arms are normally much closer together than shown in the drawing and therefore when they are spread apart and positioned between the disks 13 and 14, there results a force tending to move them towards each other and this force serves to prevent accidental disconnection. The hook 25 serves to prevent ready removal and therefore functions to hold the arms in place. Slidably connected with each arm is a spring clip 26 which may be of the construction shown in Figures 8 and 9 or of any other suitable construction. Various types of spring clips are available on the market and the one shown is merely illustrative of means and can be replaced by any other mechanical equivalent.

When a skirt is to be supported, the arms are arranged as in Figure 1 and the skirt is buttoned and suspended from the hanger in the manner indicated by dotted lines in Figure 1. Stockings can be suspended from the clips 26 or any other garment can be suspended by means of these clips. If a coat or similar article is to be supported, the arms can be moved into the position shown in Figure 4, whereupon the device functions like the ordinary coat hanger and is of great strength because there are two arms extending from each side; when the parts are in the position shown in Figure 4 the arms are resting in the depressions 18, which serve to hold them in the position shown.

From the above description, taken in connection with the drawing, it will be apparent that the coat and skirt hanger which has been described above has some marked functional advantages over the ordinary hanger more particularly in this, that it can be readily employed for supporting skirts and when the latter are in position thereon, they are kept from wrinkling and the inner surface is spread apart so as to facilitate aeration and in case a skirt is to be dried, this device serves admirably as a support during the drying period.

Particular attention is called to the positioning depressions 17 and 18 which form a useful function in connection with the type of hanger above described. The hooks 25, at the ends of arm members 21, together with elongated openings 15, like those shown in Figure 6, also perform a new and useful function in preventing the arms from being accidentally disconnected. It is evident that any force tending to disconnect the arms must operate in the direction of arrow 27 in Figure 3 and this tends to move the upper portion of the arm inwardly, whereupon the hook 25 will become operative and prevent detachment. The lengths

of the holes 15 are sufficient to permit the hooks 25 to be withdrawn when disconnection is desired.

Attention is also directed to the fact that holes 15 are elongated in a direction substantially perpendicular to the radii passing through them and that the offset ends 25 and 23 are longer than the width of the holes and shorter than the length of the holes. With this arrangement, the corresponding ends of the arms can be inserted and removed only when the planes of the arms are parallel with the longitudinal axis of the holes. This relationship is necessary for one of the disks only because an offset end like 23 in Figure 5 can be inserted into a round hole of slightly larger size as long as the other end is not attached to the other disk because the arms can then be tilted to effect this insertion. Since the disks can as well be duplicated, they are usually so made.

Having described the invention what is claimed as new is:

1. A combined coat and skirt hanger comprising, a supporting bar adapted for vertical suspension, two disks secured to the bar in fixed spaced relation, in planes perpendicular to the bar, the disks having the same number of equiangularly spaced holes, the disks being arranged with the corresponding holes positioned in the same diametrical plane, forming cooperating pairs, and a V-shaped supporting arm for each pair of holes, the limbs of each arm terminating in hooks lying in the plane of the arm and extending in the same direction, for engagement in the upper and lower hole of each pair, the hook on the lower limb being forwardly and downwardly inclined, the upper limb having a downwardly extending end portion for insertion in the corresponding hole in the upper disk.

2. A device in accordance with claim 1 in which the upper surface of at least one of the disks has depressions extending radially from each hole to position the supporting arms and hold them in a radial position.

3. A device in accordance with claim 1 in which the upper surface of at least one of the disks has depressions extending radially from each hole to position the supporting arms and hold them in a radial position and other depressions extending outwardly in a direction slightly inclined towards a common diameter.

4. A device in accordance with claim 1 in which the holes in at least one of the disks are elongated in a direction substantially perpendicular to the corresponding radii and in which the ends of the supporting arms have offset ends greater in length than the width of the holes and less than their length.

ELMO HALL.
